[57] CLAIM

The ornamental design for a package for a wafer for the
welding and/or cutting of plastic tubes, as shown and
described.

DESCRIPTION

FIG. 1 is a front elevational view of a package for a
wafer for the welding and/or cutting of plastic tubes in
accordance with this invention shown in the enclosed
condition;

FIG. 2 is a top plan view thereof;

FIG. 3 is a left side elevational view thereof with the
right side being a mirror image;

FIG. 4 is a rear elevational view thereof;

FIG. 5 is a bottom plan view thereof;

FIG. 6 is a front elevational view of the package in an
opened condition;

FIG. 7 is a top plan view thereof; and,

FIG. 8 is a perspective view thereof.

*Fig. 2.**Fig. 3.**Fig. 1.**Fig. 4.**Fig. 5.**Fig. 7.**Fig. 6.**Fig. 8.*
